E. F. BRAUCHER.

ADVERTISING DISK FOR AUTOMOBILE WHEELS.
APPLICATION FILED MAY 18, 1922.

1,432,274.

Patented Oct. 17, 1922.

UNITED STATES PATENT OFFICE.

EDWARD FRANKLIN BRAUCHER, OF DENVER, COLORADO.

ADVERTISING DISK FOR AUTOMOBILE WHEELS.

Application filed May 18, 1922. Serial No. 561,825.

To all whom it may concern:

Be it known that I, EDWARD FRANKLIN BRAUCHER, a citizen of the United States, residing in the city and county of Denver 5 and State of Colorado, have invented certain new and useful Improvements in Advertising Disks for Automobile Wheels; and I do declare the following to be a full, clear and exact description of the invention, such as 10 will enable others skilled in the art to which it appertains to make and use the same, reference being had to the accompanying drawings, and to the characters of reference marked thereon, which form a part of this 15 specification.

This invention relates to an advertising device and has special reference to a device which is adapted to be applied to the hubs of automobile wheels.

Business people such as manufacturers and storekeepers in general find it advisable at 20 all times to advertise and thus keep the public informed of the various things they have to sell and of any special bargains that they 25 may have. Merchants in general have at their disposal an effective advertising medium which they have failed so far to utilize to its fullest capacity, and this is their delivery wagons. As a usual thing, a merchant 30 will have a number of delivery wagons which each day visit every part of the town or city, but the only message that it brings is the name and location of the store, which is painted thereon and therefore cannot readily 35 be altered.

It is my object to provide each automobile wheel with a disk that is pivotally connected to the hub and counterweighted so that it will remain stationary while the wheel rotates, and to paint on the outside of such 40 disks any advertisements or announcement that the owner desires. The disks are made so that they may be readily removed and repainted or cleaned.

In order to more clearly describe my invention, I shall have reference to the accompanying drawing, in which—

Fig. 1 is a side elevation of an automobile wheel with my disk in place thereon;

Fig. 2 is a side elevation of the central portion of my disk, with parts broken away, along line 2—2, Fig. 3, for the purpose of more clearly showing the means employed for mounting the disk on the wheel hub;

Fig. 3 is a section taken on line 3—3, Fig.

1, and shows the means employed for securing the disk in place on the wheel; and

Fig. 4 is a section similar to that in Fig. 3, and shows a slight modification in the construction. 60

The same reference characters will be used to indicate the same parts throughout the several views.

In Fig. 1 I have shown a side elevation of an automobile wheel with my disk attached 65 thereto. Numeral 1 indicates the pneumatic tire casing on the wheel and numeral 2 represents the disk, on the outside of which the sign, advertisement or announcement is painted. A counter-weight 3 is secured to 70 the inside of the disk near one edge thereof, and serves to keep the disk from rotating with the wheel in a manner to be hereinafter described.

Referring now more particularly to Fig. 3, 75 it will be noticed that the disk 2 is provided centrally thereof with a hole 4 through which the hub 5 of the wheel extends. A felt washer 6 is secured to the inner surface of the disk 2 and held in place thereon by 80 any suitable means (not shown). The disk is supported on the hub 5 by means of three rollers 7 pivoted to the inner ends of bars 8 which are slidably connected to the disk by means of straps 9, whose ends are secured to 85 the disk 2 by means of rivets 10. The outer ends of bars 8 are provided with slots 11 through which a clamping bolt 12 extends. By the means just described, the disk 2 may 90 be rotatably mounted on the wheel hub 5. The rollers 7 may be adjusted to fit any size hub and to take up slack due to wear.

In order to keep the disk from moving longitudinally on the hub, I drill an opening through the end of the hub cap 13 and 95 insert a bolt 14 through the same. A round nut 15 serves to clamp the bolt securely onto the hub cap and also as a bearing. Secured centrally of disk 2 is a conical member 16 which has at its outer end a cylindrical 100 flange 17 for the reception of a cap 18. At the outer end of the member 16 I secure a transverse closure 19, which may be secured thereto by means of rivets or by solder, and which is provided with a central opening 105 engaging the outer surface of the circular nut 15. A star-shaped nut 20 serves to prevent the outward movement of the disk on the wheel. A washer 21, preferably of felt, is provided between the end of the hub cap 110

and the inside of the transverse closure 19. The space within the conical member 16 may be partly filled with grease whereby the parts are lubricated.

5 In Fig. 4 I have shown a modification in which a ring 22, having a concave outer surface, is secured to the outside of the hub 5 and serves as a runway for the rollers 7. Ring 22 may be made in different sizes so 10 as to fit the hubs of different machines.

It is apparent from the above that my advertising disk can be readily applied to and removed from the wheel, and that it is so mounted thereon as not to wobble from side 15 to side or to cause a rattling noise. The counter-weight 3 prevents the disk from rotating, with the result that the printing thereon can be read when the machine is moving, as well as when it is standing still.

20 In the drawings I have illustrated what I believe to be the preferred form of my invention, but it is apparent that minor changes may be made without departing from the spirit of my invention, and I there-

fore desire that the disclosure be considered 25 as illustrative only, as changes within the scope of the appended claim may be made without departing from the spirit of the invention.

Having now described my invention, what 30 I claim is—

An advertising device adapted to be attached to an automobile wheel hub, comprising a circular disk having a central opening therein, a plurality of radially disposed and 35 angularly spaced bars slidably adjustable on said disk, rollers secured to the end of said bars and adapted to engage the outer surface of the hub, a conical housing secured to the outside of said disk, a transverse dia- 40 phragm near the outer end of said housing, an opening in said diaphragm adapted to receive a pivot pin attached to the hub cap, a cylindrical flange projecting from the outer end of said conical housing, and a cover 45 adapted to engage said flange.

In testimony whereof I affix my signature.
EDWARD FRANKLIN BRAUCHER.
